The ornamental design for a control lever, as shown and described.

DESCRIPTION

FIG. 1 is a rear elevation view of the control lever of my new design.

FIG. 2 is a left side elevation view thereof.

FIG. 3 is a front elevation view thereof.

FIG. 4 is a right side elevation view thereof.

FIG. 5 is a top plan view thereof.

FIG. 6 is a rear top right perspective view thereof.

FIG. 7 is a rear bottom perspective view thereof; and,

FIG. 8 is a front bottom perspective view thereof.

The dashed line elements are included for the purposes of illustrating unclaimed portions of the structure of the control lever and form no part of the claimed design. The bottom surface of the control lever grip, as shown in FIGS. 7 and 8, is unclaimed.
